UNITED STATES PATENT OFFICE.

EDWIN L. ROBINSON, OF PROVIDENCE, RHODE ISLAND, ASSIGNOR OF ONE-HALF TO
HENRY J. SPOONER, OF PROVIDENCE, RHODE ISLAND.

SPRING RING.

Application filed October 5, 1921. Serial No. 505,649.

To all whom it may concern:

Be it known that I, EDWIN L. ROBINSON, a citizen of the United States, residing at Providence, in the county of Providence and

5 State of Rhode Island, have invented a new and useful Spring Ring, of which the following is a specification.

Prior to my invention hereinafter described spring-rings were commonly formed 10 in one of the following ways. One of the methods was to insert a wire in the bore of a tube to prevent the tube from being distorted in bending. The tube was then wound around an arbor into ring form.

15 The ends of the bent-up tube were not united but were left a distance apart. The inserted wire was then eaten out by acid so as to clear the bore of the tube. Another wire was then inserted in one end of the bore of the ring 20 and arranged to slide therein to open and close the space between the separated ends of the ring. The outer end of said wire was enlarged or provided with an enlargement adapted to abut against the opposite end of 25 the tube and serve as a stop to further movement of the slide in either direction.

Another common way of forming the spring-ring was to form the ring in the same manner as already described, but with the 30 tubular section shorter and to solder in the bore at one end a solid wire of less diameter than the tubular section, and another wire was inserted in the bore of the opposite end of the tubular section of the ring and arranged 35 to slide therein and to abut against the free end of the wire section of the ring to close the opening between the bored and solid end of the ring.

Both of these modes of forming a spring- 40 ring involved many operations and added considerably to the expense of manufacture.

The purpose of my invention is to provide a spring-ring of few parts and which in its construction will not require the use of 45 solder or the insertion in and subsequent removal from the tube of the form-preserving wire heretofore necessarily employed to prevent distortion of the tube in bending it into ring-shape.

50 To these ends my invention consists in the novel and useful construction, combination and arrangement of parts hereinafter de-

scribed and illustrated in the accompanying drawings in which,—

Figure 1 is a front elevation of my newly 55 invented spring-ring.

Figure 2 is a vertical section of the same.

Figure 3 is a side view of the spring-ring.

Figure 4 is a view of the reverse side of the ring showing the slidable member closed. 60

Figure 5 is a sectional view of the tubular body member of my spring-ring before a portion of it is reduced in cross section.

Figure 6 is a similar view showing the body member having portions of unequal 65 cross-section.

Like reference letters and numerals indicate like parts where they occur in the drawings.

In the drawings 1 represents the tubular 70 body of my spring-ring. 1¹ represents the portion having the larger cross-section and 1² the portion of reduced cross-section. The bore in the portion 1¹ being consequently of greater diameter than that in the portion 75 1², I term it the "larger bore". 2 represents the slidable member operating in said larger bore of the body member and arranged and adapted to open and close the space between the ends of the latter. 3 represents a spring 80 seated in the larger bore and controlling the movements of the slidable member 2. (Fig. 2.)

The body member 1 is bent on an arbor 85 into ring shape with its ends spaced a distance apart. (Fig. 6.) It is then by dies swaged so that for a portion of its extent it will be of shorter cross-section than the other portion, the bore of the two portions of the body being similarly unequal. (Fig. 6.) 90 To the edge of the body member is attached the well known form of ring 4 for connecting the spring-ring to a chain or the like. The member 2 is of the same diameter as the reduced portion of the body member and abuts 95 against it when closing the opening between the ends of the body member.

It will thus be seen that I have produced a new and useful spring-ring having an integral body member a portion of which is of 100 reduced cross-section, the portion having the larger cross-section fitted to receive the slid- able member and its controlling spring, and the portion having the reduced cross-section

fitted to serve as an abutment for the slide-
able member when the latter closes the open-
ing between the ends of the body member.
Furthermore I am by my invention able to
5 dispense with the form-preserving wire
heretofore necessarily inserted in the bore
of the tube to prevent distortion of the latter
in bending it into ring shape, and I am able
10 to fore necessarily employed to secure to-
gether the parts of a spring-ring constructed
with a tubular and a non-tubular portion.

I claim as my invention and desire to se-
cure by Letters Patent:

- 15 1. A spring-ring comprising an integral
tubular body member of reduced cross-sec-
tion for a portion of its extent, whereby the
bore in one portion of said member will be
of greater diameter than that in the other
20 portion, said body member bent into ring-
shape with its ends alined and spaced a dis-
tance apart, a spring operatively seated in
said bore of the greater diameter, and a
member slidably fitted in said bore, and ac-
25 tuated in one direction by said spring to
close the opening between said body ends,
and operative in the opposite direction
against said spring to uncover said opening.
2. In a spring-ring a one-piece tubular

body member having one portion of its 30
length of greater diameter than the other
portion, said body member bent into ring-
shape with its ends alined with each other
and spaced a distance apart, in combination
35 with a plunger reciprocatingly fitted in the
larger end of said body member and ar-
ranged to cover and uncover at will the
open space between the ends of said body
member, and a spring seated in said larger
40 end and controlling the movement of said
plunger.

3. In a spring-ring a one-piece tubular
body member bent into ring shape with its
ends alined with each other and spaced a 45
distance apart, one portion of said body
member being of greater diameter than the
other portion whereby said larger portion is
arranged and adapted to slidably receive a
reciprocating plunger covering and uncover-
ing at will the open space between the ends 50
of said body member, and the smaller por-
tion of said body member adapted to serve
as a stop limiting the movement of said
plunger in closing said open space.
